United States Patent Office.

HENRY B. BARBER, OF SCOTT, NEW YORK.

Letters Patent No. 72,588, dated December 24, 1867; antedated December 13, 1867.

IMPROVEMENT IN CHURNS.

The Schedule referred to in these Letters Patent and making part of the same.

TO ALL WHOM IT MAY CONCERN:

Be it known that I, HENRY B. BARBER, of Scott, in the county of Cortland, and in the State of New York, have invented certain new and useful Improvements in "Churns;" and do hereby declare that the following is a full, clear, and exact description thereof, reference being had to the accompanying drawings, and to the letters of reference marked thereon.

In the annexed drawings, making part of this specification, A represents the body of the churn, which may be made half round, as represented, or in any of the known and usual forms for upright churning. B represents a portion of the cover, which is stationary, and B' a movable portion of said cover. Secured upon the stationary portion of the cover is a metallic frame, G, in which a short shaft, H, has its bearings. This shaft is provided with a bevel-gear wheel, a, and with a plain plate-wheel, I, which is secured in an inclined position upon said shaft. P represents another frame, secured upon the portion B of the cover, and in which a shaft, L, has its bearings. The shaft L has upon one end a crank, and upon the other a bevel-wheel, K, which gears into the wheel a. To the upper end of an arm, d, of the frame G is pivoted, at its centre, a rocking-shaft or lever F. Depending from this lever F is an arm, J, and upon the arm, near its lower end, are two lugs, between which the rim of the wheel I plays. When the wheel I revolves with shaft H, it communicates a vibrating motion to arm J, which gives an oscillating motion to the rocking-lever F. To each end of the lever F is pivoted the upper end of a dasher-staff, C C, which extends down into the churn. These dasher-staffs are provided with cross-bars S S, portions of which are seen in fig. 2, and from these cross-bars project the arms D D. E represent vertical strips, secured to the inside of the churn.

When the shaft L is revolved, by means of its handle, the wheel K gives motion to wheel a, which revolves the wheel I. This wheel revolving, causes the lever F, through its arm, J, to oscillate, thus giving an up-and-down or vertical motion to the dasher-staffs and their arms. The agitation of the milk or cream, by the arms D, causes the butter to be set free from it.

Having thus fully described my invention, what I claim as new, and desire to secure by Letters Patent, is—

The arrangement of the dasher-staffs C C and their arms, with the oscillating lever F, arm J, shaft H, with its inclined wheel I, and the bevel-wheels a and K, substantially as and for the purpose set forth.

In testimony that I claim the foregoing, I have hereunto set my hand, this 27th day of March, 1867.

HENRY B. BARBER.
